UNITED STATES PATENT OFFICE.

BERNARD R. ANDREWS, OF BRAINTREE, AND STANLEY P. LOVELL, OF BROCKTON,
MASSACHUSETTS.

METHOD OF DRYING MATERIAL.

Application filed May 25, 1922. Serial No. 563,481.

To all whom it may concern:

Be it known that we, BERNARD R. ANDREWS, a citizen of the United States, and resident of Braintree, county of Norfolk, State of Massachusetts, and STANLEY P. LOVELL, a citizen of the United States, and resident of Brockton, county of Plymouth, State of Massachusetts, have invented an Improvement in Methods of Drying Material, of which the following description, in connection with the accompanying drawing, is a specification, like characters on the drawing representing like parts.

This invention relates to a method of drying, or evaporating liquid from, material and it has particular reference to a method adapted for use in drying material which contains or is provided with a coating of a liquid which has a constituent of such volatility that the evaporation of such constituent reduces very materially the temperature of the material.

In the industrial arts it is frequently necessary to treat some material with a liquid having a highly volatile constituent either for the purpose of impregnating or coating said material with this liquid.

It is also frequently necessary to dry the material after it has been thus impregnated or coated and under some circumstances the drying should be done without bringing the treated material into contact with a hard heated surface because of the injury to the finished product which will result by such procedure.

Further it is often necessary to perform the drying operation without reducing the temperature of the material to such a point that there is danger that moisture of condensation from the atmosphere will gather on the cooled material. The evaporating of a highly volatile constituent from any material rapidly reduces the temperature of the material and under some circumstances this reduction is such as to carry the temperature of the material below the dew-point of the surrounding atmosphere. When this condition arises moisture in the atmosphere will be condensed by the cooled material and moisture of condensation will gather on the material. As stated above there are certain lines of manufacture in which the gathering of moisture of condensation on the material has a deleterious effect thereon, as

well as necessitating the reevaporation of 55 the condensed moisture.

Merely as illustrating some manufacturing processes in which the above operations take place I might refer to that of forming shoe counters or box toe blanks by impregnating felt, fabric or similar material with a stiffening agent in liquid form and containing a volatile solvent such as alcohol, gasoline, naphtha, etc., and subsequently drying the material to evaporate the solvent 60 and leave the stiffening constituent in the material for the purpose of providing the desired stiffness. Another illustration is that involved in coating material with some emulsion or liquid coating containing a volatile constituent, and subsequently drying the coated material to evaporate the volatile constituent whereby the coating on the material becomes solid. These, however, are 65 simply illustrations of industrial-art processes to which our invention is applicable.

As stated above it is an object of our invention to provide a novel process for drying material which has been impregnated or coated with a liquid containing a volatile 70 constituent by which the drying operation can be carried out without reducing the temperature of the material below the dew-point temperature of the surrounding atmosphere thereby avoiding possibility of 75 water of condensation collecting on the dried material.

Another object of the invention is to provide an improved process by which this drying operation can be carried out without 80 bringing the material to be dried in contact with any solid substance, such for instance as a drying drum, which would be likely to injure in any way the material being treated.

The invention further has for its object to provide an improved method of drying material having various other features all as will be more fully hereinafter set forth.

In order to give a better understanding 85 of our invention we have illustrated more or less diagrammatically in the drawings one apparatus by which the method may be carried out, but we wish to state that the practise of the invention is by no means 90 limited to any particular apparatus, nor to 95 the drying of any particular material.

In the drawings, Fig. 1 is a sectional

view illustrating a device for drying web material in accordance with our hereinafter described method.

Fig. 2 is a section on the line 2—2, Fig. 1. 5 Fig. 3 is a view showing another way in which the method may be practised.

As stated above our invention is particularly applicable for drying material which has been impregnated or coated with a liquid having a constituent of such volatility that in the ordinary evaporating operation the temperature of the material will be reduced below the dew point of the surrounding atmosphere.

15 In carrying out our invention we provide means for maintaining the temperature of the material above the dew-point temperature of the surrounding atmosphere during the drying operation and without maintaining said material in contact with any solid substance. Furthermore the material is maintained at this desirable temperature without regard to the temperature of the atmosphere directly adjacent to the material.

30 One way in which this result can be accomplished is by subjecting the material to the action of radiant heat and at the same time passing a current of air across the material for assisting the evaporating process. Another way in which this end might be accomplished would be to float the material on a heated liquid while subjecting the material to the action of a drying current.

35 In Figs. 1 and 2 of the drawings we have illustrated somewhat diagrammatically an apparatus adapted to operate on the principle of subjecting the material to be dried to the action of radiant heat during the drying operation thereby to maintain said material at the desired temperature.

40 In said figures the material to be dried is indicated at 1 and may be in the form of a web or a sheet. 2 and 3 indicate two heating chambers spaced apart to form between them a space 4 through which the material to be dried may pass. Means are provided for delivering a current of air or other drying medium across both sides of the material while it is passing, or located between, the drying chambers 2 and 3 and as illustrating one way in which this may be done we have shown two air ducts 5 each having 45 a delivery nozzle 6 arranged to direct an air current over one face of the material 1. Where two nozzles 6 are employed, one on each side of the material, both sides of the material will be subjected to the action of 50 the drying current. Each of the heating chambers 2 and 3 has within it a heater of some sort, herein shown as steam pipes 7. Each of the chambers 2 and 3 will preferably have all sides thereof except that adjacent the material 1 formed of suitable heat

insulating material, and the sides adjacent the material 1 are formed of a material which will not transmit radiant heat freely but will not transmit heat by conduction to any extent. This can be accomplished by making the sides 8 of glass and by double glazing the sides the amount of heat by conduction is practically nil while radiant heat will be freely transmitted.

55 In using this apparatus for drying material the latter is placed in the space 4 between the two heating chambers and is subjected to the action of the drying medium delivered through the nozzles 6. At the same time the steam coils 7 are utilized to 60 generate heat in the heating chambers 2 and 3 and heat of radiation will be transmitted freely through the glazed sides 8 onto the material 1 thus heating the latter. The amount of heat which is generated in the 65 steam coils will be sufficient so that the radiant heat will be received by the material 1 in sufficient quantities to maintain the temperature of the material above the dew-point temperature of the surrounding 70 atmosphere.

75 Where the material 1 is coated or impregnated with a liquid having a volatile constituent the evaporation of this volatile constituent will, of course, reduce the temperature of the material 1 and by properly regulating the amount of heat radiated from the steam coils it is possible to maintain the temperature of the material 1 above the dew-point temperature thus obviating the 80 possibility that any moisture of condensation from the atmosphere can gather on the material. Furthermore by using the two nozzles and delivering a current of drying 85 medium against the material 1 the latter can be carried through the space 4 without appreciable contact with any heated support or rest, and, therefore, it is possible to use this method and apparatus in drying 90 web material of a character which will be 95 injured by being brought into contact with a heated solid object during the drying operation.

95 The material 1 being dried may be fed through the space 4 or may be placed there- 100 in and allowed to remain for a proper length of time and then removed therefrom.

105 In Fig. 3 we have shown diagrammatically another way in which the invention 110 may be practised. In said figure 9 represents a vessel containing some liquid 10 such as mercury and 11 indicates suitable means for heating the liquid. 12 indicates a nozzle which is movable over the liquid 10 to flow 115 thereon a film or web 13 of the material to be dried which may be in liquid or semi-liquid form. A suitable drying medium may be blown over the web 13 from the nozzles 14 for the purpose of drying the latter. The 120 mercury or other liquid 10 will be main- 125 130

tained at a sufficiently high temperature to keep the web 13 at a temperature above the dew-point of the surrounding atmosphere so that during the operation of evaporating

5 the liquid from the film 13 the temperature of said film will not at any time fall below the dew-point of the surrounding atmosphere.

One method now commonly used for drying material containing a volatile liquid where it is important to prevent moisture of condensation from gathering on the material as it dries, is to dehumidify the air before it is used in the drying operation 10 so that the drying will be done with air that contains no moisture that can condense. This method of drying involves the use of a very expensive apparatus for thus dehumidifying the air and this is one disadvantage resulting from said method.

Another method which is now commonly used for drying such material is to retard the drying operation by carrying it on an atmosphere highly saturated with the vapor of 15 the solvent, as under such circumstances the evaporation will take place slowly and there will be a correspondingly small reduction in temperature due to such evaporation. This method, however, has the disadvantage that 20 it involves considerable fire hazard. In order to avoid both of the above difficulties it has been proposed to use in certain industrial arts solvents having a high boiling point so that in order to evaporate the solvents 25 completely a temperature must be used which is above any dew-point temperature of the surrounding atmosphere. This, however, is not satisfactory because of the high cost of such solvents.

10 An advantage inherent in our improved method is that the desired drying operation can be carried out at a relatively small expense and without the necessity of employing an expensive apparatus for dehydrating the air. Furthermore our method can be carried 15 out without any fire hazard because a sufficient amount of air may be used at all times to keep the vapor which is floated from the material diluted below the ignition point.

15 We desire to state that the apparatus which is diagrammatically shown herein has been used merely for the purpose of illustrating how the method might be practised and without any intent to limit the invention to any particular apparatus.

I claim.

1. The steps in the method of drying material carrying volatile liquid which consist in evaporating said liquid from the material 10 at such a rate as would normally cause a reduction of the temperature of the material

below the dew-point of the surrounding atmosphere, and maintaining the material at a temperature above said dew point by radiant heat.

2. The steps in the method of drying material carrying volatile liquid which consist in evaporating said liquid from the material at a sufficiently rapid rate to cause normally a reduction of the temperature of the material 15 below the dew-point of the surrounding atmosphere, and maintaining the material at a temperature above said dew point without contact with a solid heated surface.

3. The steps in the method of drying material which carries a volatile liquid, which consist in passing an air current over the material and thereby producing evaporation of said liquid from the material at such a rate as would normally cause a reduction of 20 the temperature thereof below the dew-point of the surrounding atmosphere, and subjecting said material to the action of radiant heat in sufficient quantities to maintain the material at a temperature above said dew-point.

4. The steps in the method of drying material which carries a volatile liquid, which consist in evaporating in a space open to the atmosphere said liquid from the material at such a rate as would normally cause a reduction of the temperature of the material below the dew-point of the surrounding atmosphere, and maintaining the material at a temperature above said dew-point by radiant heat.

5. The steps in the method of drying material which carries a volatile liquid, which consist in passing an air current over the material at a rate to cause normally by said evaporation a reduction in the temperature of the material to a point below that of the air current and below the dew-point of the surrounding atmosphere, and subjecting said material to the action of radiant heat in 100 sufficient quantities to maintain the material at a temperature above said dew-point.

6. The steps in the method of drying material carrying a volatile liquid, which consist in evaporating said liquid from the material at such a rate as would normally cause a reduction in the temperature of the material below the dew-point of the surrounding atmosphere, and maintaining the material at a temperature above said dew-point 110 by radiant heat as distinguished from heating by conduction.

In testimony whereof, we have signed our names to this specification.

STANLEY P. LOVELL.
BERNARD R. ANDREWS.
